Primary Examiner — Austin Murphy

CLAIM

The ornamental design for a controller for storage shelving unit, as shown and described.

DESCRIPTION

FIG. 1 is a top perspective view of the controller for storage shelving unit showing our new and ornamental design;

FIG. 2 is a front elevation view thereof;

FIG. 3 is a back elevation view thereof;

FIG. 4 is a side elevation view thereof;

FIG. 5 is an alternate side elevation view thereof;

FIG. 6 is a top plan view thereof; and,

FIG. 7 is a bottom plan view thereof.

The portions of the controller for storage shelving unit shown in broken lines in the figures attached hereto form no part of the claimed design.

1 Claim, 7 Drawing Sheets
